ROLLING MILL

Ilario Properzi, Milan, Italy

Application February 5, 1953, Serial No. 335,346

2 Claims. (Cl. 80—36)

The present invention relates generally to rolling mills for metal rods or the like, and more particularly to an improved rolling mill which comprises a train or series of aligned rolling units each contributing progressively to reduce the cross-section of metal stock introduced into the mill.

Rolling mills having a train of rolling units each with a pair of rolling members are known, but these have the disadvantage in that it is a simple matter for the metal stock being rolled to undergo undesired rotation from one rolling unit to the other which produces defects in the rolled product. The rotational tendencies of the stock have been overcome in the past by the use of three rolling members for each rolling unit. These rolling members in each unit are placed at angles of 120° to each other and exert a concentric pressure over the complete surface of the wire and, by displacing the rolling members of successive units angularly by 60°, the rod may be passed through the rolling mill from one unit to another without being subjected to rotational stresses so that the properties of the ultimate product are substantially improved.

Despite the undoubted advantages of using three rolling members in each unit with the units arranged in the aforescribed manner, constructional difficulties have been encountered in providing a rolling mill in which a train of such units is utilized. One difficulty is the fact that the drive shafts of successive rolling units must be placed alternately above and below the rolling axis due to the fact that the rolling members of successive units are displaced 60° with respect to one another. Moreover, as a result of the alternate locations of successive drive shafts, the rotational drive thereof must be alternately reversed to maintain the rolling in one direction.

Yet another difficulty is the fact that the rate of rotation of the rolling members of successive rolling units must be progressively increased because of the elongations in the rod due to the reduction of cross-section thereof as it passes from one unit to another. Theoretically the required rate of rotation of the successive rolling units is a function of the rolled cross-section produced thereby on the rolled rod. However, it has been found in practice that strict adherence to such theoretical rotational speed is not possible. The reason for this is that the theoretical values are subject to material variations when different types of metal stock are rolled and for different temperature conditions. Consequently, for satisfactory operation it is necessary that the rolling mill be capable of simple adjustment to accommodate different metals and for different temperature conditions. Unless such an adjustment is provided, the rolled rod undergoes excessive tensional and compressional strains which result either in fracture or in unsatisfactory operation of the mill.

It is an object of the present invention to provide an improved rolling mill in which the difficulties and

2

problems encountered in the art are overcome for all practical purposes.

A further object of the invention is to provide such an improved rolling mill which includes a series of rolling units in which the rolling members of such units are driven in a simple, efficient and highly improved manner.

Yet another object of the invention is to provide such an improved rolling mill including a series of rolling units in which such units are readily adjustable so that the mill may accommodate different metals and operate under different temperature conditions, thereby increasing the flexibility of the mechanism.

Yet another object of the invention is to provide such an improved rolling mill which includes a series of individual rolling units which are so constructed and driven that the overall dimensions of the rolling mill are reduced to a practical minimum.

A still further object of the invention is to provide such an improved rolling mill which may be readily accommodated to produce rolled metal rod of a wide variety of diameters.

A feature of the invention is the provision of an improved rolling mill comprising a train of rolling units with drive shafts positioned alternately above and below the rolling axis, in which only one of a group of such units is directly driven and transmits rotational motion to other units in the group in the proper direction and at appropriate different speeds for each unit, by means of a simple replaceable pinion and gear arrangement. This provides an extremely simple, rugged and accessible assembly, and also allows the various rolling units to be placed in close proximity one with the other to decrease the overall dimensions of the rolling mill.

Another feature of the invention is the provision of an improved rolling mill which is constructed so that the individual rolling units constituting the mill may be expeditiously excluded from the train for cleaning purposes, or for enabling the metal stock to be withdrawn from the mill at any intermediate point when it is required to produce a rod of a cross-section which is larger than would be the case were it to traverse the whole train.

Another feature of the invention is the provision of an improved rolling mill in which the rolling cross-section in each rolling unit may be conveniently adjusted to accommodate different metals having different moduli of elasticity or to compensate for different temperature conditions.

The above and other features of the invention which are believed to be new are set forth with particularity in the appended claims. The invention itself, however, together with further objects and advantages thereof may best be understood by reference to the accompanying drawing in which:

Fig. 1 illustrates one type of rolling unit for incorporation into the rolling mill of the invention having its drive shaft positioned below the rolling axis,

Fig. 2 is a longitudinal section through the rolling unit illustrated in Fig. 1,

Fig. 3 is a cross-sectional view of a second type of rolling unit for incorporation into the rolling mill having its drive shaft located above the rolling axis,

Figs. 4 and 5 are detailed views of a portion of the rolling unit of Fig. 3.

Fig. 6 is a front elevation of the complete rolling mill constructed in accordance with the invention and arranged on a common base,

Fig. 7 is a plan view of the rolling mill shown in Fig. 6,

Fig. 8 is a rear elevational view of the driving means for the rolling mill of Figs. 6 and 7,

Fig. 9 is a cross-sectional view taken along the line 9—9 of Fig. 8,

Fig. 10 is a rear perspective view of the transmission mechanism for the various rolling units included in the rolling mill shown in Figs. 6 and 7, and

Fig. 11 is a side view, partly in section, of the rolling mill particularly illustrating the construction for excluding a rolling unit from the rolling train.

The rolling mill of the invention includes a base structure and a plurality of rolling units supported on the base to define a train of rolling passes spaced along a rolling axis. A corresponding plurality of drive shafts are respectively included in the rolling units and extend therefrom along axes transversing the aforesaid rolling axis. A plurality of driving spindles are rotatably mounted on the aforesaid base in respective alignment with the drive shafts and removably coupled thereto. A driving mechanism imparts rotation to one of the spindles which, in turn, transmits rotation to the other spindles through a gear transmission mechanism. Finally, adjustable means are provided for individually moving the rolling units transversely of the aforesaid rolling axis to an inoperative position with the corresponding drive shafts and spindles out of engagement.

As previously pointed out, the rolling mill of the invention includes a series or train of individual rolling units which successively have their driving shafts positioned in alternation above and below the rolling axis. The rolling unit of Fig. 1 represents one of those of the train which have their driving shafts located below the rolling axis and, as shown in this figure, the rolling unit comprises three rolling members 1, 2 and 3 angularly displaced 120° relative to each other. Rolling member 3 is mounted on a drive shaft 4, and members 1 and 2 are respectively rotatably mounted on shafts 9 and 10. The driving shaft 4 extends beyond the left-hand side of the unit transversely to the rolling axis and terminates in a splined projection. Rolling member 3 has two bevel pinions 5 and 6 on each side thereof likewise secured to drive shaft 4, and which transmit rotary motion from the drive shaft to a further pair of bevel pinions 7 and 8 respectively secured to the rolling members 1 and 2.

The rolling axis of the unit is indicated as 11 and the three rolling members 1, 2 and 3 cooperate to enclose a rolling cross-section about this axis. The rolling cross-section is illustrated as of a hexagonal shape in Fig. 1, although it is to be understood that it could be circular or any other appropriate shape.

The horizontal drive shaft 4, which is disposed below the rolling axis 11, is mounted in bearings on a bracket 12, and the shafts 9 and 10 are supported respectively in bearings in brackets 13 and 14. As shown in Fig. 2, the various elements of the rolling unit are firmly held together by side closure plates 15 and 16, and the overall dimensions of the unit in the longitudinal direction of the roll train are reduced to a minimum and are only a little larger than the diameter of each roll.

The rolling unit of Fig. 3 is similar to that of Fig. 1 with the exception that the rolling members are displaced angularly by 60° with respect to the corresponding rolling members of Fig. 1, with the drive shaft disposed above the rolling axis. The unit of Fig. 3 may, for example, be incorporated in the rolling mill as the next succeeding unit to that of Fig. 1. In the case of the unit of Fig. 3, the rolling cross-section may be approximately triangular and of smaller area than that of the preceding unit, such as shown in Fig. 1, so that the metal stock passing therethrough is further reduced in cross-sectional area. It is preferred that rolling in the mill from one rolling unit to another be alternately from a hexagonal to a substantially triangular section to eliminate any possible tendency for the stock being rolled to rotate as it passes from one unit to the next.

Figs. 6 and 7 illustrate the complete train or rolling mill which is made up of an appropriate number of rolling

units of the type illustrated in Figs. 1 and 3 alternating along the rolling axis. The particular train is composed of 13 separate rolling units arranged on a common base

- 21, the units bearing even numbers from 22-34 being of 5 the type shown in Fig. 1, and those with the odd numbers 23-33 being of the type shown in Fig. 3. The rotation of the drive shafts of the units 22-34 is in the opposite direction to the rotation of the drive shafts of the odd numbered units 23-33, this being due to the fact 10 that the first group of drive shafts is positioned beneath and the second group of drive shafts is above the rolling axis. The metal stock is introduced into the rolling unit 22 at the left-hand side of the drawing and proceeds to the right of the drawing through the successive units. 15 The stock has its cross-sectional area successively reduced in each successive pass and emerges as a wire of a relatively small cross-sectional area from unit 34.

Fig. 8 shows the mechanism for driving a series of rotary spindles 35-47 mounted on the common base 21 in respective alignment with drive shafts of the various rolling units, and which have the function of transmitting rotary motion to the drive shafts. As has already been indicated, the spindles are arranged in groups, two such groups being illustrated in Fig. 8, with one spindle only 20 in each group being directly driven. The group of spindles numbers 35-41 in Fig. 8 respectively engage the drive shafts of units 22-28 of Fig. 6, and the second group of spindles 42-47 engage respectively the drive shafts of units 29-34.

30 A driving motor 48 is arranged beneath the base 21 and transmits rotary motion to a drive shaft 52 by means of a pair of transmission pulleys 49 and 50 which are interconnected by a drive belt 51. A pair of shafts 57 and 58 rotatably supported in bearings in base 21 and 35 extending at right angles to shaft 52 are driven respectively by the bevel wheel pairs 53, 54 and 55, 56. Shaft 52 has a central bearing 59 and a double resilient coupling 60 for compensating for any possible mounting irregularities. Shafts 57 and 58 have a pair of spur 40 wheels 61 and 63 at their respective upper ends which engage respective toothed crowns 62 and 64. In this manner, the rotary spindle 45 for one group of units and the rotary spindle 39 for the other group are directly driven. Spindles 39 and 45 will hereinafter be referred to as the main spindles for the groups concerned.

The driving means for spindle 39, and the manner in which the spindle cooperates with the drive shaft of rolling unit 26, is more clearly shown in Fig. 9 which is a sectional view taken along the line 9-9 of Fig. 8. In Fig. 9, the lower pair of bevel wheels 55 and 56 cooperate to drive the shaft 58 which, in turn, drives spur wheel 61, the latter engaging the toothed crown 62. Toothed crown 62 is secured to spindle 39 which has a toothed gear wheel 65 keyed to its outer end and a socket 114 formed at its inner end, the socket having internal teeth which removably engage the projecting splined end of the drive shaft of rolling unit 26. As also shown in Fig. 9, the base 21 of the rolling mill has an upper horizontal mounting surface 112 which supports the various rolling units of the rolling train. The base also includes a vertical wall 113 which rotatably supports the various spindles, such as spindle 39, for driving the drive shafts of the rolling units.

65 Adverting again to Fig. 8, the rotary speed of main spindle 45 must be greater than that of main spindle 39 since the metal stock is assumed to be introduced into the right hand end of the machine as shown in Fig. 8, and has its cross-sectional area materially reduced as it travels from the rolling unit driven by spindle 39 to the unit driven by spindle 45. The speed differential of these two spindles is achieved by providing a predetermined different transmission ratio in the bevel wheels 53, 54 as compared with the bevel wheels 55, 56.

The complete rolling train or mill, and particularly

the transmission mechanism for the various rotary spindles 35—37 and the engagement of these spindles with the drive shafts of rolling units 22—34, is shown in Fig. 7. As previously pointed out, the first group of spindles is driven from the main spindle 39 to which the toothed crown 62 and gear wheel 65 are rigidly connected, whereas the second group is driven from the main spindle 45 which has a similar toothed crown 64 and gear wheel 66 affixed thereto. The transmission mechanism for one group of spindles is shown in perspective in Fig. 10, it being understood that a similar arrangement is used for the other group. As previously noted, it is necessary that the various spindles of each group be rotated at different speeds, and also that successive spindles be rotated in alternate directions, this being achieved by the transmission mechanism of Fig. 10.

As previously pointed out, the main spindle 45 derives rotary motion from the main driving means directly through the toothed crown 64 rigidly connected thereto. Gear 66 is also rigidly connected to the main spindle and engages a gear 67, the latter being rotatably mounted on shaft 69 and rigidly secured to a further gear 68 of smaller diameter. Gear 68 meshes with a rotatably mounted reversing gear 70, the latter engaging a gear 71 fixed to spindle 44. In this manner, rotation at a reduced speed is imparted to spindle 44, which is positioned above the rolling axis, in a direction opposite to the rotation of spindle 45 below the rolling axis. It is to be noted that gears 66, 70 and 71 are of equal diameter and have the same number of teeth, the reduction in rotary speed of spindle 44 with respect to that of spindle 45 being determined solely by the ratio of the diameters and the number of teeth of gears 67 and 68. This simple arrangement provides for high power transmission in a relatively small space.

Gear 70, in turn, transmits rotary motion to gear 75 on spindle 43 through a pair of gears 72, 73 rotatably mounted on shaft 74, the larger diameter gear 72 engaging gear 70 and the smaller diameter gear 73 meshing with gear 75. In this manner, spindle 43 is rotated in the opposite direction to spindle 44 and with a decreased speed. In a similar fashion, rotation is transmitted from gear 75 to spindle 42 so that the latter spindle rotates in the opposite direction to that of spindle 43 and with a decreased speed relative thereto.

At the left-hand side of Fig. 10, gear 66 engages a gear 76 which, together with a gear 77 of larger diameter rigidly connected thereto, is rotatably mounted on a shaft 78. Gear 77 engages a rotatably mounted reversing gear 79 which, in turn, meshes with a gear 80 secured to spindle 46. In this manner, spindle 46 is rotated in a direction opposite to the rotation of spindle 45 and with increased speed relative thereto. Gear 79, likewise, drives a gear 81 rigidly secured to spindle 47 through a pair of affixed rotatable gears 82 and 83, gear 83 being smaller than gear 82 so that spindle 47 rotates in a direction opposite to the rotation of spindle 46 and at an increased speed.

With the transmission described above, it can be seen that spindles 42—47 are rotated at progressively greater speeds and in alternately opposite directions. In the gear train, not only are the gear wheels 66, 70, 71, 75, 79, 80, 81, etc., of the same diameter and have the same number of teeth; but all the gear pairs 67/68, 72/73, 76/77, 82/83, etc., are also identical and are merely inserted and alternately reversed in the transmission mechanism to the right and to the left of the main spindle 45, in accordance with the speed increase or speed reduction required. This arrangement not only greatly simplifies the transmission mechanism but provides for rapid and convenient interchanging of the elements for replacement purposes.

Since the transmission ratio of the various gears of Figs. 7 and 10 is invariable, means is provided in the rolling mill for adjusting the cross-sectional area of the

rolling pass defined by each rolling unit so that precise adjustment for different types of metal stock and for varying temperature conditions can be made. This adjustment is illustrated in Figs. 3, 4 and 5. As shown in these figures, drive shaft 17 is rotatably mounted in bearings in a bracket 84, the bracket being secured by bolts 85 and 86 to the sides 87 and 88 of the casing of the rolling unit. In this manner, the drive shaft 17 is rigidly held for rotation about a horizontal axis and is immovable with respect to that axis. Rolls 19 and 20, on the other hand, are rotatably mounted on shafts 89 and 90, the shafts being respectively supported in bearings in brackets 91 and 92 which, in turn, are secured to the sides 87 and 88 of the rolling unit by bolts 93 and 94 respectively passing therethrough.

As more clearly shown in Fig. 5, bolt 94 is mounted in the sides 87 and 88 of the roller unit so that it can be readily shifted towards or away from the rolling axis by means of screws 95, 96 and 97, 98 threaded into these sides. Adjustment of screws 95, 96 and 97, 98 moves bracket 91 and, therefore, roll 19 towards or away from the rolling center by a small amount to control the cross-sectional area of the rolling pass defined by the rolling members. These minor displacements of bracket 91 are kept within the engagement 99 between previously described bevel pinions on drive shaft 17 and shaft 89. As shown in Fig. 4, bracket 91 is disposed in a guide 101 in side 87 and a similar guide in side 88 to insure that the displacement takes place parallel to the original position so that the shape of the rolling pass remains unchanged for variation in its cross-sectional area. It is desirable that a similar lateral shifting adjustment may be provided for bolt 93 of bracket 92 so that the same configuration can be maintained for the rolling pass as its dimensions are altered. In this manner, although the rolling speed of each rolling unit is invariable, the cross-sectional area of each rolling pass may be adjusted to accommodate a wide variety of metals and different temperature conditions.

As previously pointed out, the rolling mill of the present invention also has the feature in that individual rolling units may be excluded from the rolling train for cleaning purposes or when the rolling requirements dictate a lesser number of rolling units. This feature is more clearly shown in Fig. 11 and, as illustrated in this figure, each rolling unit is mounted on base 112 by means of a threaded rod 108 which is secured to the base at its left-hand end. Rod 108 has a sleeve 106 coaxial therewith, the latter having internal threads engaging the threads on the rod and the sleeve being secured to a rolling unit, here designated as 110. Sleeve 106 has a squared end 107 which may be turned by means of a key applied thereto, and rotation of sleeve 106 causes the entire rolling unit to move to the right of the drawing with its splined drive shaft 4 disengaging its corresponding rotary spindle 114, the latter being rotatably mounted on the upstanding bracket portion 111 and 113 of the base in the manner previously described and having an internally toothed socket. In this manner, by rotating sleeve 106, the rolling unit may be moved along sliding path 109 away from the rolling axis of the rolling mill and into an inoperative position. When it is desired again to place rolling unit 110 into an operative position, it is merely necessary to rotate sleeve 106 in the opposite direction and retract the unit.

The present invention provides, therefore, an improved rolling mill which is constructed to provide a relatively large number of rolling passes in a relatively small space and which incorporates a unique driving arrangement in which the rolling passes are arranged in driving groups so that the relatively large number of such units may be driven all with high power. It is of course to be understood, that when an additional number of passes is required, further groups may be provided. The invention also provides a rolling mill in which the cross-sectional

areas of the various rolling passes may be adjusted for different conditions in a simple and convenient manner, and in which various rolling units may be expeditiously removed from the rolling terrain when such as desired.

While a particular embodiment of the invention has been shown and described, modifications may be made and it is intended in the appended claims to cover all such modifications as fall within the true spirit and scope of the invention.

I claim:

1. A machine for the continuous rolling of a metal rod or the like, including in combination, a base structure, a succession of rolling units supported on said base structure, each including three rolling members angularly spaced with respect to one another, said rolling members of successive ones of said units being angularly displaced from one unit to the next and defining a series of rolling passes spaced along a rolling axis, said rolling units being movable horizontally on said base along an axis transverse to said rolling axis, a first group of drive shafts for a first group of said rolling units respectively extending along horizontal axes perpendicular to said rolling axis and above said rolling axis, a second group of drive shafts for a second group of said rolling units respectively extending along horizontal axes perpendicular to said rolling axis and below said rolling axis, said shafts of said rolling units being positioned in alternation along said rolling axis and said drive shafts of said first and second groups being rotatable in opposite directions to drive said rolling units, with said shafts having splined extremities, a first group of spindles rotatably mounted on said base in respective alignment with said drive shafts of one of said groups, a second group of spindles interposed with the spindles of said first group in respective alignment with said drive shafts of the other of said groups, said spindles having a splined socket portion for engaging a corresponding one of said splined shafts, a driving mechanism for imparting rotational motion to one of said spindles, a first series of gear wheels respectively affixed to said spindles of said first group, a second series of gear wheels respectively affixed to said spindles of said second group, a series of reversing gear wheels rotatably mounted on said base in respective en-

gagement with said gear wheels of said first series, a series of like pairs of coaxial mutually affixed gear wheels of unequal diameters rotatably mounted on said base respectively interposed between said reversing gear wheels and said gear wheels of said second series, with one gear wheel of each of said pairs engaging a corresponding one of said reversing gear wheels and with the other gear wheel of each of said pairs engaging a corresponding one of said gear wheels of said second series, a first elongated threaded member mounted on said base adjacent each said movable rolling unit and extending across said rolling axis, and a second elongated threaded member mounted on said rolling unit in coaxial and threaded relation with said first threaded member, so that rotation of one of said threaded members imparts individual horizontal movement to said movable rolling unit transverse to said rolling axis between an operative position in which said splined extremity of the drive shaft thereof engages said socket and an inoperative position in which the drive shaft of said movable rolling unit is disengaged from said socket and said movable unit is displaced entirely from said rolling axis.

2. A machine as defined in claim 1 wherein said rolling members of said rolling units are mounted on shafts, means operatively connected to at least one of said shafts to adjust the rolling member to and away from said rolling axis.
